Inventor

PASCHAL CONVERSE, OF NEW HAVEN, CONNECTICUT.

Design No. 3,238, dated November 17, 1868.

DESIGN FOR A CLOCK-CASE.

The Schedule referred to in these Letters Patent and making part of the same.

To all whom it may concern:

Be it known that I, PASCHAL CONVERSE, of New Haven, in the county of New Haven, and State of Connecticut, have invented a new Design for Clock-Case; and I do hereby declare the following, when taken in connection with the accompanying drawing, and the letters of reference marked thereon, to be a full, clear, and exact description of the same, and which said drawing constitutes part of this specification, and represents a front view.

This invention relates to a design for what are known as cottage-clocks, and consists in the peculiar form of the top, which presents five angles, that is to say, through the centre of the dial the upper part of the clock represents one-half of a ten-sided figure, and gives to the case a much neater appearance than when formed

in a half octagon or half circle, as has heretofore been the common design for this class of clocks.

The frame of the door around the dial is a circle in form, resting upon a base, which forms the lower part or panel of the door, and the whole case rests upon a base, the whole forming a new design, as fully shown and illustrated in the accompanying drawing.

Having fully described my invention,

What I claim as new, and desire to secure by Letters Patent, is—

The design for a clock-case, herein fully described and illustrated.

PASCHAL CONVERSE.
